UNITED STATES PATENT OFFICE.

SAMUEL VEYON, OF EAST PALESTINE, OHIO.

BRICK.

No. 839,792.

Specification of Letters Patent.

Patented Dec. 25, 1906.

Application filed July 10, 1906. Serial No. 325,464.

To all whom it may concern:

Be it known that I, SAMUEL VEYON, a citizen of the United States of America, residing at East Palestine, in the county of Columbiana and State of Ohio, have invented certain new and useful Improvements in Bricks, of which the following is a specification, reference being had therein to the accompanying drawings.

10 This invention relates to bricks, and more particularly to an ornamental brick having a facing of opaque glass or like vitreous material.

15 The primary object of the invention is to provide a brick with a veneer or facing secured to the body of the brick in such a manner as to firmly connect the facing without liability of its being cracked or defaced by expansion and contraction.

20 I preferably employ a refuse material from potteries known as "bisque," admixed with Portland cement to form the body of the brick, to one edge of which a facing of opaque glass is secured by mechanical securing means, as well as by a suitable adhesive material.

25 The construction of the improvement will be fully described hereinafter in connection with the accompanying drawings, which 30 form a part of this specification, and its novel features will be particularly set forth in the appended claims.

35 In the drawings, Figure 1 is a view in perspective of a brick embodying the invention. Fig. 2 is a transverse section of the same. Fig. 3 is a perspective view of a modified embodiment of the invention. Fig. 4 is a longitudinal section of the brick shown in Fig. 3. Fig. 5 is a perspective view of a modified form 40 of the fastener for securing the facing to the body of the brick, and Fig. 6 is a transverse sectional view of a further modification.

45 The body 1 of the brick is molded from a refuse material of potteries known as "bisque," combined with Portland cement, and the facing 2, preferably of opaque glass, is applied to the outer face of the brick and secured thereto by an adhesive material, preferably by a cement consisting of gum-arabic admixed with ball-clay, and also by metallic fasteners bent to provide edge plates 3 and inclined anchoring-plates 4, the latter being firmly embedded in the body of the brick during the process of molding, while

the edge plates overlap the edges of the glass 55 facing 2 and a small portion of the brick body adjacent to the edges of the glass facing and lie flush with the surfaces of the brick. The metallic fasteners may be applied along either the longitudinal or the vertical edges 60 of the brick and facing, and I have shown in the drawings both of these applications of the invention.

In Figs. 1 and 2 the fastening-plates extend along the longitudinal edges of the vitreous 65 facing, the inclined anchoring-plates 4 being embedded in the body of the brick in such relation to the facing as to cause the parallel projecting plates 3 to overlap the opposite longitudinal edges of the facing, the outer 70 edges 5 of the plates 3 being nearly flush with the outer surface of the facing, thus securing and protecting the glass facing throughout its length.

In Figs. 3 and 4 the metallic fasteners are 75 applied to the ends of the brick, thus securing the vitreous facing at its ends.

In Fig. 5 a modification of the fastener is shown in which the inclined anchoring-plate 4^a is formed with a plurality of openings 6, 8c through which the plastic material composing the body of the brick passes to more firmly embed the fastener therein. In this modified form of the fastener the edge plate 3^a is creased longitudinally, as at 7, giving 85 the outer edge 8 of the plate a slight inward inclination.

In the modification shown in Fig. 6 I employ a holder comprising a strip 9 of either this sheet metal or chemically-prepared paper cemented to the body of the brick and overlapping the facing, as shown. This construction differs from that shown in the other figures by omitting the anchoring-plate 4.

An important feature of the present invention is the employment of a composition of the refuse material known in the potter's art as "bisque" and Portland cement, for the reason that the bisque has had burned out of it all chemical elements which would render 100 the material susceptible to expansion and contraction by changes in temperature, and the surface of the brick to which the facing is applied being of a vitreous character cracking or defacement of the opaque facing 105 through expansion and contraction of the body of the brick is reduced to the minimum.

The utility of the supplemental fasteners

is obvious, they affording substantial mechanical securing means for the facings, at the same time permitting such slight expansion and contraction as has not been eliminated by the character of the material employed.

I would have it understood that the invention includes all such modifications and variations in structure as may be resorted to without departing from the terms and scope of the invention:

What I claim, and desire to secure by Letters Patent, is—

1. A brick having a facing of vitreous material, in combination with metallic fasteners, embedded in the body of the brick and having projecting plates overlapping the opposite edges of the facing.

2. A brick having a body portion consisting of a composition of bisque and cement and a facing of opaque glass applied to the outer face of the body of the brick, and secured thereto by adhesive material, in combination with supplemental metallic fasteners, each comprising an anchoring-plate embedded in the body portion of the brick, and an edge plate overlapping the adjacent edge of the facing.

3. A brick comprising a body portion, and a facing of opaque glass, or like vitreous material, in combination with metallic fasteners each bent to provide an inclined anchor-

ing-plate embedded in the body portion of the brick, and parallel edge plates overlapping the opposite edges of the facing.

4. A brick comprising a body portion, and a facing of opaque glass or like vitreous material cemented to the outer surface of the brick in combination with oppositely-disposed metallic fasteners each consisting of an inclined anchoring-plate embedded in the body of the brick, and a projecting edge plate, to overlap the adjacent edge of the facing.

5. An ornamental brick comprising a body portion consisting of a composition of cement and a refuse pottery material known as "bisque," and a facing of opaque glass cemented upon the outer face of the brick, in combination with oppositely-disposed metallic fasteners embedded in the body of the brick and having projecting edge plates overlapping opposite edges of the facing.

6. A brick having a body portion, and a facing of opaque vitreous material, secured thereto by adhesive material, and fastening-strips secured to the body of the brick and overlapping the opposite edges of the facing.

In testimony whereof I affix my signature in the presence of two witnesses:

SAMUEL VEYON.
